CUSHIONING AND FLOW CONTROL VALVE
John S. Pilch, % Ware Machine Works, Inc.,
P.O. Box 140, Ware, Mass.
Filed May 17, 1960, Ser. No. 29,755
10 Claims. (Cl. 121—40)

This invention relates to a new and improved boom cushioning and flow control valve for hydraulic systems and to a hydraulic system employing said valve and has particular reference to a new and improved valve and hydraulic system for controlling the movement of various mechanisms such as the boom on a hydraulic trencher, the push arms on a hydraulic loader, or any other hydraulic circuit.

An object of the invention is to provide a new and improved valve and hydraulic system of the type set forth which acts as a positive seal when the unit is not in operation to eliminate the load creeping downward, or if the levers on the main control valve were accidentally moved while the hydraulic pump was not operating, the valve of the present invention will eliminate the possibility of oil escaping from the cylinder in question which would cause the mechanism to drop downward.

Another object is to provide a valve and system of the type set forth which, when the control valve is moved to lower the load, starts the lowering operation gradually and without a sudden burst of speed.

Another object is to provide a device of the type set forth which cushions the end of the travel of the apparatus.

Other objects and advantages of the invention will be apparent from the following description taken in connection with the accompanying drawing.

Referring to the drawing:

FIG. 1 is a longitudinal sectional view of a hydraulic cylinder embodying the present invention;

FIG. 2 is a fragmentary sectional view illustrating a step in the operation of the device;

FIG. 3 is a fragmentary sectional view, generally similar to FIG. 2, but illustrating another step in the operation of the device; and

FIG. 4 is a schematic view of a hydraulic system embodying the invention.

Referring more particularly to the drawing wherein similar reference characters designate corresponding parts throughout, the hydraulic system shown in FIG. 4 comprises a main control valve 10 adapted to receive hydraulic fluid under pressure through hydraulic line 11 and having an outlet 12 connected by hydraulic line 13 to port 14 on the down side of cylinder 15. Hydraulic line 13 is also connected by the line 16 to the port 17 in the end of cylinder 18. Cylinder 18 has the port 19 connected by hydraulic line 20 to the port 21 on control valve 10.

Cylinder 18 has the portion 18a with port 18b which is connected by hydraulic line 21 to port 22 on the lift side of cylinder 15.

In cylinder 15 is provided the double acting piston 23 connected to the ram 24.

In port 17 of cylinder 18 is provided the member 25 having the pilot orifice 26 as hereinafter described. In cylinder 18 is provided the cushion timing piston 27 which has the O ring seal 28 in its periphery.

The piston 18 is provided with the end cap 18c having the extension portion 18a and in end cap 18c is provided a seat 29 for cushioning valve 30 which is provided at its end adjacent timing piston 27 with ports 31 which are always adapted to be positioned beyond the end of seat 29.

Cushioning valve 30 has the spring seat portion 32 70 engaging coil spring 33 which has its opposite end engaging the inner surface of threaded cap 34 and on the side

of cushioning valve 30 opposite spring seat 32 are provided the ports or passages 35.

It will be noted that the ports 35 are graduated in size and are spaced from each other a considerable distance and these ports could be replaced by one long tapered slot in order that the plunger open the proper distance depending upon the volume of fluid being supplied by the pump which eliminates jerky movement of the equipment and assures the elimination of vacuum in the cylinder.

With the present device, as the operator lowers his load, the cushion timing piston 27 is in the position shown in FIG. 1 and as the operator moves the main control valve into hold position, closing off the lines from the cylinder to the oil reservoir there would be a sudden jar if a heavy load on the end of a boom or a loader bucket full of material was stopped suddenly. With the present valve, as the load attempts to come down, this load creates pressure on the lift side of the lift cylinder forcing fluid through port 19 and through flow control cushioning plunger 30 gradually moving the cushioning timing piston to the left and fluid then would flow through port 26 to the down side of the lift cylinder through line 13 and port 14. As this operation continues, oil would be escaping on a graduated scale because of the graduated ports or orifices 35 and as soon as the cushion timing piston 27 has traveled to the full extent on the left, the plunger would be closed as shown in FIG. 3, and the boom could not travel downward any more. It can be clearly seen that with the use of this valve, after the operator has manually closed off the main control valve 10, the trencher boom or loader arms can travel downward a predetermined distance and at a graduated pace and be automatically brought to a smooth stop.

The valve of the present invention acts as a positive seal by preventing fluid passing and/or leaking from the lift side of the lift cylinder through the main control valve 10 and this prevents the trencher boom from creeping downward while the trencher is not in use, and even more importantly, acts as a safety device by preventing the boom from dropping if any person moves the control handle of control valve 10 while the trencher is not in use. The operation of the valve as a positive seal is as follows:

At all times, when the main control valve is closed, the flow control plunger 30 is closed against seat 29, see FIG. 3, by pressure exerted from the lift side of the lift cylinder through line 21 and port 18b. This prevents oil passing out of the lift side of the lift cylinder if the main control valve leaks or is opened accidentally while the trencher is not running.

The flow control plunger 30 is unseated to connect port 22 with the main control valve only when hydraulic pressure from the pump is applied to the down side of the lift cylinder 15. This pressure passes from port 12 to port 14 through line 13 into the down side of the lift cylinder 15 and exerts pressure against the lift cylinder piston 23. The lift cylinder piston 23 is unable to move at that moment because line 21 is closed by seated plunger 30. This pressure being applied to the down side of lift cylinder 15 also passes through line 16 through pilot orifice 26 and pushes cushion timing piston 27 to the right which in turn pushes flow control plunger 30 to the right unseating the same and allowing fluid to flow from port 22 to the main control valve.

As stated above, the valve also acts as a cushioning valve when starting to lower the trencher boom. As explained above, when hydraulic pressure is applied to the down side of cylinder 15, fluid cannot escape from the lift side of cylinder 15 until fluid from the down side of said cylinder has passed through the pilot orifice 26 and moved the cushion timing piston 27 to the right, thereby unseating plunger 30. As plunger 30 begins to unseat

fluid flows through the graduated orifices or ports 35, completing the circuit from port 22 to the main control valve. The orifices or ports 35 being graduated, restrict the flow of fluid at first and then as each is opened, allow more fluid to flow until their total area is more than that of the lines in the system and complete full flow is accomplished. This graduated restriction, from no flow to full flow, when done in a short period of time, acts as a cushion and because of this, the trencher boom starts to move downward very slowly and then gradually speeds up to full downward speed making downward operation smooth and free of jerks.

The valve, as stated above, also acts as a cushioning valve when stopping downward movement of the trencher boom. In this arrangement, when the boom is being lowered, pressure applied to the down side of the lift cylinder 15 holds the flow control and cushioning plunger 30 open, as described above in connection with the action of the valve as a positive seal, and when the operator closes the main control valve to stop downward movement, the flowing cycle takes place which cushions the stopping of the downward movement of the trencher boom and associated parts:

The closing of the main control valve by the operator stops the flow of fluid through lines 13 and 11 and due to the momentum and weight of the boom and associated parts, pressure is exerted on the lift side of the lift cylinder 15, while the pressure immediately drops on the down side of the lift cylinder.

The pressure already present between piston 27 and orifice 26 escapes through pilot orifice 26 through lines 16 and 13 to the down side of the lift cylinder 15, thereby lowering the pressure in the chamber between piston 27 and pilot orifice 26 and as this pressure drops, pressure from the lift side of the lift cylinder is exerted on the side of piston 27 opposite pilot orifice 26 by flowing through the orifices 35 in the flow control plunger 30 and causing the cushion timing piston 30 to move toward piston 27. Pressure on the right side of timing piston 27 and on the right end of flow control plunger 30 keeps the cushion timing piston 27 moving toward orifice 26 and due to the graduated orifices in the flow control plunger 30, the more the cushion timing piston 27 moves to the left, the more the restriction until the flow control plunger 30 is fully seated as shown in FIG. 3. This graduated cutdown of flow cushions the downward movement of the trencher boom and it is gradually brought to a stop.

The flow control valve also acts to provide anti-cavitation to the down side of the lift cylinder during downward movement of the trencher boom. In this operation, as the trencher boom is being lowered due to the weight of the trencher bucket, dipper stick, etc., there is a tendency for the fluid from the lift side of the lift cylinder to escape at a faster rate than the pump through the manual control valve supplies fluid to the down side of the lift cylinder 15. With the present valve, as shown in FIG. 3, fluid from the lift side of the cylinder cannot escape until line 16 is pressurized and fluid pressure that is escaping from the lift side of the lift cylinder piston is attempting to keep plunger 30 closed. The pump supplying fluid to the down side of the lift cylinder 15 and pressurizing line 16, due to the cushion timing piston being larger in diameter than the flow control and cushioning plunger 30, forces the cushion timing piston 27 to move to the right and open plunger 30 and keeps it open only as long as there is pressure in line 16. It will be understood that plunger 30 is opened only the proper distance or amount, as an example, if the motor were idling and the pump were turning out only a small volume of fluid then the plunger 30 might conceivably be moved over very little as the first few orifices 35 would be large enough to take the flow of fluid being supplied by the pump whereas, if the pump were running at a higher pace, plunger 30 would be moved a greater distance to the right and so on and, therefore, at no time

can line 16 be under a vacuum which would allow the pump to cavitate.

From the foregoing, it will be seen that I have provided new and improved means for obtaining all of the objects and advantages of the invention.

I claim:

1. In a device of the type set forth, a cylinder, a piston in said cylinder, a restricted orifice for controlling the passage of fluid to said cylinder on one side of said piston, a fluid passage connected to said cylinder on the opposite side of said piston, a chamber communicating with said cylinder on the side thereof opposite said restricted orifice, a valve for controlling the passage of fluid from said cylinder to said chamber, said valve being adapted to be moved in one direction by said piston, resilient means for normally urging said valve in a direction opposing movement thereof by said piston, and said valve having a passage therethrough connecting said cylinder with said chamber, and port means in said chamber adapted to be connected to a hydraulic line.
2. In a device of the type set forth, a cylinder, a piston in said cylinder, a restricted orifice for controlling the passage of fluid to said cylinder on one side of said piston, a fluid passage connected to said cylinder on the opposite side of said piston, a chamber communicating with said cylinder on the side thereof opposite said restricted orifice, a valve for controlling the passage of fluid from said cylinder to said chamber, said valve being adapted to be moved in one direction by said piston, resilient means for normally urging said valve in a direction opposing movement thereof by said piston, and said valve having a passage therethrough connecting said cylinder with said chamber, said valve having port means of progressively increasing area as said valve is moved into said chamber by said piston, and port means in said chamber adapted to be connected to a hydraulic line.
3. In a device of the type set forth, a cylinder, a piston in said cylinder, a restricted orifice for controlling the passage of fluid to said cylinder on one side of said piston, a fluid passage connected to said cylinder on the opposite side of said piston, a chamber communicating with said cylinder on the side thereof opposite said restricted orifice, a valve for controlling the passage of fluid from said cylinder to said chamber, said valve being adapted to be moved in one direction by said piston, resilient means for normally urging said valve in a direction opposing movement thereof by said piston, and said valve having a passage therethrough connecting said cylinder with said chamber and port means in said chamber adapted to be connected to a hydraulic line.
4. In a device of the type set forth, a cylinder, a piston in said cylinder, a restricted orifice for controlling the passage of fluid to said cylinder on one side of said piston, a fluid passage connected to said cylinder on the opposite side of said piston, a chamber communicating with said cylinder on the side thereof opposite said restricted orifice, a valve for controlling the passage of fluid from said cylinder to said chamber, said valve being adapted to be moved in one direction by said piston, resilient means for normally urging said valve in a direction opposing movement thereof by said piston, and said valve having a passage therethrough connecting said cylinder with said chamber, said valve having port means of progressively increasing area as said valve is moved into said chamber by said piston and port means in said chamber adapted to be connected to a hydraulic line.
5. In a device of the type set forth, a cylinder, a piston in said cylinder, a restricted orifice for controlling the passage of fluid to said cylinder on one side of said piston, a fluid passage connected to said cylinder on the opposite side of said piston, a chamber communicating with said cylinder on the side thereof opposite said restricted orifice, a valve for controlling the passage of fluid from said cylinder to said chamber, said valve being

adapted to be moved in one direction by said piston, resilient means for normally urging said valve in a direction opposing movement thereof by said piston, and said valve having a passage therethrough connecting said cylinder with said chamber, said valve being adapted to be closed by said resilient means and opened by the force of fluid in said cylinder from a hydraulic line and passing through said restricted orifice, and port means in said chamber adapted to be connected to a hydraulic line.

6. In a device of the type set forth, a cylinder, a piston in said cylinder, a restricted orifice for controlling the passage of fluid to said cylinder on one side of said piston, a fluid passage connected to said cylinder on the opposite side of said piston, a chamber communicating with said cylinder on the side thereof opposite said restricted orifice, a port in said chamber, a valve for controlling the passage of fluid from said cylinder to said chamber, said valve being adapted to be moved in one direction by said piston, resilient means for normally urging said valve in a direction opposing movement thereof by said piston, and said valve having a passage connecting said cylinder with said chamber, said restricted orifice being connected by a hydraulic line to the control valve and the down side of a cylinder and said port in said chamber being connected by a hydraulic line to the lift side of a cylinder with said fluid passage on the side of said cylinder opposite said restricted orifice being connected to the control valve.

7. In a device of the type set forth, a cylinder, a piston in said cylinder, a restricted orifice for controlling the passage of fluid to said cylinder on one side of said piston, a fluid passage connected to said cylinder on the opposite side of said piston, a chamber communicating with said cylinder on the side thereof opposite said restricted orifice, a port in said chamber, a valve for controlling the passage of fluid from said cylinder to said chamber, said valve being adapted to be moved in one direction by said piston, resilient means for normally urging said valve in a direction opposing movement thereof by said piston, and said valve having a passage connecting said cylinder with said chamber, said valve having port means of progressively increasing area as said valve is moved into said chamber by said piston, said restricted orifice being connected by a hydraulic line to the control valve and the down side of a cylinder and said port in said chamber being connected by a hydraulic line to the lift side of a cylinder with said fluid passage on the side of said cylinder opposite said restricted orifice being connected to the control valve.

8. In a device of the type set forth, a cylinder, a piston in said cylinder, a restricted orifice for controlling the passage of fluid to said cylinder on one side of said piston, a fluid passage connected to said cylinder on the opposite side of said piston, a chamber communicating with said cylinder on the side thereof opposite said restricted orifice, a port in said chamber, a valve for controlling the passage of fluid from said cylinder to said chamber, said valve being adapted to be moved in one direction by said piston, resilient means for normally

urging said valve in a direction opposing movement thereof by said piston, and said valve having a passage connecting said cylinder with said chamber and port means in said chamber adapted to be connected to a hydraulic line, said restricted orifice being connected by a hydraulic line to the control valve and the down side of a cylinder and said port in said chamber being connected by a hydraulic line to the lift side of a cylinder with said fluid passage on the side of said cylinder opposite said restricted orifice being connected to the control valve.

9. In a device of the type set forth, a cylinder, a piston in said cylinder, a restricted orifice for controlling the passage of fluid to said cylinder on one side of said piston, a fluid passage connected to said cylinder on the opposite side of said piston, a chamber communicating with said cylinder on the side thereof opposite said restricted orifice, a port in said chamber, a valve for controlling the passage of fluid from said cylinder to said chamber, said valve being adapted to be moved in one direction by said piston, resilient means for normally urging said valve in a direction opposing movement thereof by said piston, and said valve having a passage connecting said cylinder with said chamber, said valve having port means of progressively increasing area as said valve is moved into said chamber by said piston and port means in said chamber adapted to be connected to a hydraulic line, said restricted orifice being connected by a hydraulic line to the control valve and the down side of a cylinder and said port in said chamber being connected by a hydraulic line to the lift side of cylinder opposite said restricted orifice with said fluid passage on the side of said cylinder being connected to the control valve.

10. In a device of the type set forth, a cylinder, a piston in said cylinder, a restricted orifice for controlling the passage of fluid to said cylinder on one side of said piston, a fluid passage connected to said cylinder on the opposite side of said piston, a chamber communicating with said cylinder on the side thereof opposite said restricted orifice, a port in said chamber, a valve for controlling the passage of fluid from said cylinder opposite said restricted orifice to said chamber, said valve being adapted to be moved in one direction by said piston, resilient means for normally urging said valve in a direction opposing movement thereof by said piston, and said valve having a passage connecting said cylinder with said chamber, said valve being adapted to be closed by said resilient means and opened by the force of fluid in said cylinder from a hydraulic line and passing through said restricted orifice, said restricted orifice being connected by a hydraulic line to the control valve and the down side of a cylinder and said port in said chamber being connected by a hydraulic line to the lift side of a cylinder with said fluid passage on the side of said cylinder opposite said restricted orifice being connected to the control valve.
